UNITED STATES PATENT OFFICE

2,171,655

FREQUENCY DRIFT COMPENSATOR

John Kelly Johnson, Chicago, Ill., assignor to
 Wells-Gardner & Company, Chicago, Ill., a
 corporation of Illinois

Application March 15, 1937, Serial No. 130,945

2 Claims. (Cl. 175—41.5)

The circuits of radio receiving sets have a tendency to drift in frequency response due to variations in temperature which cause shifts in frequencies in tuning condensers or coils, in dielectric constants, and in power factors of various insulating materials.

These produce a very substantial frequency drift which causes difficulty in tuning particularly when the receiving set is equipped with an automatic tuning device such as the "telephone dial" which returns the tuning condensers of the several stages to a definite predetermined setting for a desired broadcasting station. In this case it becomes necessary to provide means for insuring that a given setting of the tuning condensers corresponds to a given radio frequency in order that the set may be properly tuned for the desired station at all temperatures to which the set is likely to be subjected.

An object of this invention is to provide means for compensating for variations in temperature whereby the receiving set will not drift materially at any point within its range from a predetermined setting.

This and other objects as will hereinafter appear are accomplished by this invention which is fully described in the following specification and shown in the accompanying drawing in which the figure is an enlarged section through a condenser used to automatically compensate for changes in the set due to temperature.

Frequency drift due to variations in temperature is particularly noticeable in superheterodyne circuits where the tuning is of the predetermined type which is operated by means of a telephone type dial, push buttons or the like, so that for a given station, all the tuning elements are given predetermined settings. Except for the frequency drifts referred to the set would then be tuned for the given frequency. Differences in temperature however cause the set to drift from the desired frequency and this drift is mainly in the oscillator stage and this drift can be substantially corrected for in that stage alone.

The embodiment illustrated comprises a compensating capacitor which may be placed in a radio circuit to compensate for temperature variations. This capacitor comprises a metal disk 11 and a bimetal disk 12 separated by a disk of suitable dielectric material 13 all held together

by means of a bolt 14. The disk 12 is composed preferably of brass and invar. Soldering lugs 15 and 16 are held in contact with the disks 11 and 12, respectively, by this bolt, the disk 11 and lug 15 being suitably insulated from the bolt 5 by means of an insulating tube 17 and an insulating washer 18.

The dielectric disk 13 is made of a composition containing rubber and is substantially unaffected by moisture conditions and the washer 10 10 13 is covered with a suitable wax 19 to the depth of about $\frac{1}{2}$ of an inch so that it is also substantially impervious to moisture.

The disks 11 and 12 are normally slightly reversely arched, but this arching is purposely exaggerated in the drawing in order to make this point evident. The shape of the disk 11 will be substantially constant at all temperatures such as will be usually encountered by a radio receiving set, but the bimetal disk 12 will change 20 its curvature with variations in temperature. These changes in the degree of curvature of the disk 12 produce variations in the capacity of the condenser and the variations in the capacity thus produced in the compensating capacitor are 25 so chosen as to substantially balance the changes in capacity of the parts of the oscillator circuit of the radio receiving set in which it is used.

Thus it has been found by actual test that by the use of such a compensating capacitor, the 30 frequency drift of the set due to capacity changes as above pointed out which are caused by temperature variations is substantially corrected.

I claim:

1. A compensating capacitor comprising two 35 metal plates, an insulator therebetween, and means for holding the plates in juxtaposition, one of said plates being curved spherically and made of bimetal adapted to change its curvature and hence the capacitance of the capacitor with 40 differences in temperature.

2. A compensating capacitor comprising two metal plates, a solid insulator therebetween, and a bolt extending centrally therethrough for holding the plates in juxtaposition, one of said plates being curved spherically, the curved plate being adapted to change its curvature with respect to the other plate with differences in temperature whereby the capacitance of the capacitor will 45 change.

JOHN KELLY JOHNSON.
